INVENTOR.
Arthur Atwater Kent
BY
Cornelius D. Ebert
his ATTORNEY.

UNITED STATES PATENT OFFICE.

ARTHUR ATWATER KENT, OF ARDMORE, PENNSYLVANIA.

RADIOSPEAKER.

Application filed October 30, 1925, Serial No. 65,727. Renewed June 27, 1928.

My invention relates to amplifying telephones, and especially loud speakers or radio speakers utilized in connection with radio receiving apparatus.

5 In accordance with my invention, a diaphragm, preferably conical and of large diameter, is vibrated, in accordance with sound-representing current, by a vibratile armature operatively related to pole piece

10 structure of a magnet system, with readily accessible means manually operable to adjust the gap between the vibratile armature and pole piece structure without need for access to the adjusting screw or element itself.

15 Further in accordance with my invention, the adjusting screw or element is provided with a shoe or tip which engages the pole piece structure and with respect to which the adjusting element or screw is rotatable.

20 My invention resides in structure and arrangement of parts of the character herein-after described and claimed.

For an illustration of one of the various forms my invention may take, reference is 25 to be had to the accompanying drawings, in which:

Fig. 1 is a vertical sectional view, partly in elevation, of a radio speaker embodying my invention.

30 Fig. 2 is a fragmentary side elevation of the structure shown in Fig. 1.

Fig. 3 is a rear elevational view of the magnet system provided with air gap adjusting means.

35 Fig. 4 is a front elevational view of the structure shown in Fig. 3.

Fig. 5 is a horizontal sectional view, partly in plan, taken on the line 5—5 of Fig. 3.

40 Fig. 6 is a vertical sectional view, partly in elevation, taken on the line 6—6 of Fig. 3.

Referring to the drawing, 1 is a base or support to which is secured by the screw 2 a bracket member 3 to which is secured by the rivet or equivalent member 4 one of the

45 arms or spokes 5 radiating from a central supporting member 5^a and carrying at their outer ends the guard member 26, which embraces and protects, but stands free and spaced from, the periphery of the diaphragm 50 D, of paper or other suitable material, conical in form and of relatively large diameter.

As indicated, the magnet system may be of the character disclosed in my prior application Serial No. 32,875 and in application

Serial No. 41,031, filed, respectively, May 26 55 and July 2, 1925.

The substantially rectangular frame or yoke 6 of the magnet system is secured to the supporting member 5^a by screws 6^a extending through the spacing members 7 and having 60 applied thereto on the rear of the support 5^a the nuts 8.

Secured to the frame or yoke 6 by the same screws 6^a are the inwardly extending pole pieces 9, in alignment with each other and 65 between whose inner ends is left an air gap. Surrounding the pole pieces 9 are the windings or coils C traversed by the voice- or sound-representing current, such as exists, for example, in the anode circuit of a detector or 70 audio frequency thermionic amplifier as commonly utilized in radio receiving apparatus.

The yoke 6 is preferably permanently magnetized, having poles of opposite signs at 75 opposite ends thereof adjacent the points of attachment thereto of the pole pieces 9, 9, whereby at the inner and adjacent ends of the pole pieces 9 are exhibited opposing north and south magnetic poles.

Substantially mid way between the ends 80 of the yoke or frame 6 and extending transversely of and spaced from the pole pieces 9, 9, is the vibratile armature member 10. In the yoke 6 is a hole 11 in which is riveted the hollow or tubular shank 12 integral with the 85 spacer member 13, to which one end of the armature 10 is secured by the screw 14.

Integral with the yoke 6 is the bridging member 15, offset from the plane of the yoke 6 on that side thereof opposite to the armature 10. Threaded through the bridging member 15 is the adjusting element or screw 16, whose end adjacent the pole pieces 9 is recessed at 17 to receive the pivot pin 18 upon or integral with the shoe or tip 19, of 95 brass or other non-magnetic material, which has a flat face bridging the pole pieces 9 and engaging their rear faces.

The manually operable adjusting arm or lever 20 is threaded upon the screw 16, the 100 lock nut 21, threaded upon screw 16, serving to lock the adjusting arm 20 in predetermined angular position upon the screw 16 in fixed relation thereto, whereby manual rotation of the arm 20 about the axis of the screw 16 rotates the latter, causing its advance or recession, and thereby adjusting the pole pieces 9, 105 by flexing them with respect to the yoke 6,

toward or away from the armature 10, the tip or shoe 19 remaining substantially fixed with respect to the pole pieces, but partaking of adjustment longitudinally of the axis of 5 the screw 16 upon rotation of the latter with respect to the shoe 19. Adjacent the screw 16 and nut 21, and the inner end of the adjusting lever 20, the aforementioned support 5^a is recessed or cupped, as indicated at 5^b.
 10 The arm or lever 20 extends outwardly preferably to a distance greater than the diameter of the supporting hub or member 5^a and at its outer end has the offset end or handle 20^a grasped by the operator in effecting 15 the adjustment of air gap between armature and pole pieces.

By the structure described, the adjustment of gap between the armature and pole pieces is possible at any time and quickly, even 20 while the apparatus is in operation, without need for access directly to the adjusting screw 16, whereby the sensitiveness of the telephone magnet system or the amplitude of vibration of the diaphragm may be adjusted quickly 25 without interruption of operation, to suit the varying orders of magnitude of sound-representing current of the receiving apparatus which may vary between wide limits for 30 several reasons, such, for example, as variation of distances over which the radio reception is effected.

The mode of attachment of the adjusting arm 20 to the screw 16 is such as to provide adjustment of the arm with respect to the 35 adjusting screw, which latter is adjusted to the usual or normal position at the factory and the arm 20 locked in such position upon and to the screw 16 that the ultimate user may then effect adjustment of sensitiveness 40 and amplitude between wide limits without changing the adjustment of the arm 20 upon the screw 16, though this may be effected by loosening the lock nut 21, determining the new adjustment of the arm 20 with respect 45 to the screw 16, and thereafter tightening the nut 21.

Threaded into the vibratile armature 10 is the pin 22, to which is secured by set screw 23 the sleeve 24, to which are secured the 50 conical sheet metal members 25, to which is secured the diaphragm D, whose periphery is embraced by and spaced from the guard 26.

What I claim is:

1. The combination with a telephone magnet system comprising pole pieces spaced from each other and from a vibratile armature member, of means for effecting adjustment of the air gap between said armature member and said pole pieces comprising a 60 shoe bridging said pole pieces and engaging them frictionally to prevent rotation of said shoe, and an adjusting member engaging and movable with respect to said shoe.

2. The combination with a telephone magnet system comprising pole pieces spaced

from each other and exhibiting at their adjacent ends opposite magnetic polarities, and a co-acting armature member, of means for effecting adjustment of the air gap between said armature member and said pole pieces 70 comprising a shoe of non-magnetic material bridging said pole pieces and engaging them frictionally to prevent rotation of said shoe, and an adjusting member engaging and movable with respect to said shoe. 75

3. The combination with a telephone magnet system comprising pole pieces spaced from each other and from a vibratile armature member, of means for effecting adjustment of the air gap between said armature member and said pole pieces comprising a rotatable axially movable adjusting member, and a relatively fixed shoe engaged by said adjusting member bridging said pole pieces and engaging them frictionally to prevent rotation of said shoe. 85

4. The combination with a telephone magnet system comprising pole pieces spaced from each other and from a vibratile armature member, of means for effecting adjustment of the air gap between said armature member and said pole pieces comprising a rotatable axially movable adjusting member, a 90 relatively fixed shoe member bridging said pole pieces and engaging them frictionally to prevent rotation of said shoe member and engaged by said adjusting member, one of said last named members having a recess and the other having a pivotal extension disposed in said recess. 100

5. An amplifying telephone comprising a support having a depressed central portion, a telephone magnet system carried by said support, a diaphragm between which and said support said magnet system is disposed, 105 a rotatable adjusting member for adjusting the air gap of said magnet system, and a manually operable arm secured to said adjusting member and disposed in said depressed portion. 110

6. An amplifying telephone comprising a support having a recess, a telephone magnet system fixedly mounted on said support, a diaphragm between which and said support said magnet system is disposed, a rotatable 115 adjusting member carried by said magnet system and disposed adjacent said recess, and a manually operable arm secured to said adjusting member adjacent said recess and extending radially therefrom. 120

7. An amplifying telephone comprising a support having a recess, a telephone magnet system fixedly mounted on said support, a diaphragm between which and said support said magnet system is disposed, a rotatable 125 adjusting member carried by said magnet system and disposed adjacent said recess, and a manually operable arm secured to said adjusting member adjacent said recess and disposed between said support and said magnet 130

system and extending radially from said adjusting member.

8. An amplifying telephone comprising a support, a telephone magnet system fixedly mounted on said support, a diaphragm between which and said support said magnet system is disposed, a rotatable adjusting member for adjusting the air gap of said magnet system, and a manually operable arm secured 10 to said adjusting member and extending radially therefrom to a position for access from the opposite side of said support.

9. An amplifying telephone comprising a support, a telephone magnet system carried 15 by said support and comprising a vibratile armature and pole pieces, a conical diaphragm of large diameter vibrated by said armature, a rotatable adjusting member for adjusting the air gap between said pole pieces and ar- 20 mature, and an adjusting arm secured to said adjusting member and disposed within the conical diaphragm.

10. An amplifying telephone comprising a support, a telephone magnet system carried 25 by said support and comprising a vibratile armature and pole pieces, a conical diaphragm of large diameter vibrated by said armature, a rotatable adjusting member for adjusting the air gap between said pole pieces and ar-

mature, and an adjusting arm secured to said 30 adjusting member and disposed within the conical diaphragm between said support and magnet system.

11. An amplifying telephone comprising a support, a telephone magnet system carried 35 by said support and comprising a vibratile armature and pole pieces, a conical diaphragm of large diameter carried by said armature, said magnet system disposed between said support and said diaphragm, a rotatable ad- 40 justing member for adjusting the air gap be- between said pole pieces and armature, and a manually operable arm secured to said ad- 45 justing member between said support and said magnet system and disposed within said dia- phragm.

12. An amplifying telephone comprising a support, a telephone magnet system carried by said support and comprising a vibratile armature and pole pieces, a conical diaphragm 50 of large diameter vibrated by said armature, a rotatable adjusting member for adjusting the air gap between said pole pieces and ar- mature, and a manually operable member 55 secured to said adjusting member and dis- posed within the conical diaphragm.

ARTHUR ATWATER KENT.
